KNIFE SHARPENER OR SIMILAR ARTICLE

Joseph P. Hussar, Weymouth, Mass., assignor to
The Alden Speare's Sons Company, Cambridge,
Mass., a corporation of Massachusetts

Application January 15, 1954, Serial No. 28,533

Term of patent 14 years

(Cl. D37—1)

To all whom it may concern:

Be it known that I, Joseph P. Hussar, a citizen of the United States, residing at Weymouth, in the county of Norfolk and Commonwealth of Massachusetts, have invented a new, original, and ornamental Design for a Knife Sharpener or Similar Article, of which the following is a specification, reference being had to the accompanying drawing, forming a part thereof, in which:

Fig. 1 is a side elevation of a knife sharpener embodying my new design;

Fig. 2 is a top plan view thereof;

Fig. 3 is a front elevation thereof; and
Fig. 4 is a rear elevation thereof.

I claim:

The ornamental design for a knife sharpener or similar article, substantially as shown.
